(Continued)*Primary Examiner* — Elizabeth A. Albert(74) *Attorney, Agent, or Firm* — Jie Yang; ZANIP**CLAIM**

The ornamental design for a paint brush carrying bag, as shown and described.

DESCRIPTION

FIG. 1 is a front perspective view of a paint brush carrying bag, showing my new design;
 FIG. 2 is a rear perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof; and,
 FIG. 9 is a perspective view thereof, showing the paint brush carrying bag in a bended position.
